CLAIM

The ornamental design for a bottle stopper or similar article, substantially as shown and described.

DESCRIPTION

FIG. 1 is a top plan view of a bottle stopper or similar article showing my new design;

FIG. 2 is a front view in elevation thereof, the back view being identical to the front;

FIG. 3 is a bottom plan view thereof;

FIG. 4 is a side view in elevation, each side being identical;

FIG. 5 is a cross-sectional view thereof taken along the lines 5—5 of FIG. 2; and

FIG. 6 is a cross-sectional view thereof taken along the lines 6—6 of FIG. 2.

All beveled surfaces are plane surfaces.
